METHOD AND MACHINE FOR KNITTING

Kenneth Howie, Norristown, Pa., assignor to
 Wildman Mfg. Co., Norristown, Pa., a corpora-
 tion of Pennsylvania

Application December 22, 1939, Serial No. 310,627

35 Claims. (Cl. 66—82)

The invention relates to a single unit full fashioned hosiery knitting machine on which both the leg and foot are knitted, as distinguished from the practice of knitting the leg portion of the fabric on one machine, and then transferring said fabric to a footer, on which the foot of the stocking is produced as a continuation of the leg fabric.

In a marketed machine of this general type, as devised by me, a series of instep transfer points are employed to take off the loops from the instep needles, hold them while the heel tabs are being knit, and thereafter restore said instep loops to the needles.

In said known machine, it was the practice to spread the heel tabs laterally and impale on the needles lying out beyond the instep series, certain loops of said heel tabs, so that knitting of the foot could be proceeded with as a continuation of the leg and heel tab fabric. This act of impaling loops of the heel tabs upon the needles just referred to was done by hand. Difficulty has been experienced, especially in fine gauges, say of 54 cut, in performing said hand operation of impaling the heel tabs on the needles, and in order to facilitate this work of the attendant, a wale of enlarged loops was formed near the inner selvage edge of the heel tab which enabled the operator to impale this portion of the heel tab fabric onto the needle with comparative ease.

These wales of enlarged loops, one in each heel tab, were formed, as just stated, near the inner selvages of the heel tabs, but with say two or three wales of ordinary size loops between said wale of enlarged loops and the extreme inner selvages, the initial loops of these wales being of fine gauge, and having been knit off from their needles during the knitting of the heel tabs, the operator had to exercise unusual care in impaling them on the needles for further knitting (of the 40 foot).

One object of this invention is to relieve the operator of this delicate operation by automatically restoring these fine gauge initial loops of the said two or three wales, lying intermediate the 45 wale of enlarged loops and the inner selvage, onto the needles.

For this purpose, broadly speaking, extra transfer points are provided in the present invention on the same bar which carries the instep points, but out beyond the series of said instep transfer points. These extra transfer points take off or receive from the needles the two or three fine gauge loops, which, for convenience, may be called initial heel tab loops, hold them while the 55

heel tabs are being knit, and thereafter restore them to the needles, following which the operator, by hand, impales the wale of enlarged loops of heel tabs onto the needles, so that the knitting of the foot fabric now can be proceeded with as a continuation from the heel tabs and with a full complement of loops made up of those impaled by hand and those restored automatically to the needles.

In carrying out this automatic action just mentioned, the few fine gauge initial loops of the heel tabs, i. e., belonging to the wales lying between the wale of enlarged loops and the inner selvages, are taken off or received from their needles by the extra transfer points above mentioned by so operating the instep bar that the said extra points will operate at the back or beardless side of the needles, and because the said extra transfer points and instep points are carried, as stated, by the same bar, i. e., the instep bar, the action of the instep points in relation to their respective needles is substantially the same as is the action of the extra transfer points in relation to those needles from which the few loops of the first course of the heel tab are removed, and onto which said few loops are restored for continuing the knitting of the foot. That is to say, in taking off the instep loops and the two or three loops of the initial course of the heel tabs, the said points, instep and extra, all operate simultaneously on the beardless side or back of the needles. In this way, the subsequent knitting of the heel tabs is not interfered with because the beards may be pressed for casting off the loops as the knitting of the heel tabs progresses, as in ordinary practice.

After the heel tabs have been knit, the two or three loops of the initial course are impaled automatically onto the needles for continuing the knitting to produce the foot.

I have mentioned "two or three" as the number of heel tab loops that are automatically taken care of at the ends of the instep loops, but the invention is not limited to any particular number of said loops, this number being dependent upon the number of wales lying between the wale of enlarged loops and the inner selvage edge of the heel tabs.

Figure 1 is an enlarged view showing the portion of the needle row which knits part of the instep and part of a heel tab, the last course of the leg fabric before the heel tabs are knit being upon the needles, and the loop receiving points being in position to receive their loops.

Fig. 2 shows the same portion of needle row,

several heel tab courses having been knit and the loop receiving points being in the loops which they received.

Fig. 3 shows the same portion of the needle row, the heel tabs having been knit and cast off, and the loop receiving points being in position to return their loops to the needles.

Fig. 4 shows the same portion of the needle row, the heel tab being turned outwardly and the loops of one of its wales being located upon the needles.

Fig. 5 is an enlarged front view of a loop receiving point.

Fig. 5a is a side view of the point of Fig. 5.

Fig. 40 is a plan view of a portion of the righthand part of the machine.

Fig. 41 is a detail of a part of Fig. 40.

The points 6 which receive loops from the needles 2 and subsequently deliver these loops to the same needles, are carried in a cross-bar 5 (Figs. 18 and 19) of a frame 1 which is pivotable about a bearing at 12. The points 6 are spaced apart the same as the spacing of the needles, and are sufficient in number to receive all of the instep loops and the next three loops at each end of the instep loops. Three such loops have been selected to illustrate the invention, but a larger or less number may be received at each end of the series of instep loops. When reference is hereinafter had to the three end loops, it is intended to comprehend a different number which may be handled in a similar manner in any particular circumstance. Reference may be had to Figs. 1 and 2 for an illustration of the loops which, with the apparatus here shown, are received by points 6.

In Figs. 1 and 2, only the portion of the fabric adjacent the corner formed by the inner selvage of one of the heel tabs and the instep is shown, since the corresponding corner of the other heel tab is similar, and the remaining portion of the heel tab and instep should be evident. The course at the top of Fig. 1 is the last course of the leg of the fabric knitted before the first course of the heel tabs is knit. The loops *h* and the other loops to the left of them in Fig. 1 are the loops of the fabric onto which the heel tab courses will be knit, and are hereinafter referred to as heel tab foundation loops. The loops *i* and the other loops to the right of them in Fig. 1 are

the ones ordinarily designated instep loops, and from which no knitting will be performed while the heel tabs are being knit. This is evident from Fig. 2, which shows a number of heel tab courses knit from the loops *h*, but no courses knit from the loops *i* of the instep. The loops *i* and *h* have consequently moved away from the row *d*—*d* of needles *2* in Fig. 2.

The instep loops *i* and the loops *h* are received from their needles on points *6* at the time that the course in which they lie is knit off, as will be described in detail. The heel tabs are then knit, the instep and heel tab foundation points remaining in their loops *h* and *i*. After the heel tabs have been completed and have been cast off of the needles, it is necessary to return to the needles the instep loops *i* as well as the three loops *h* at the ends of the instep loops. In Fig. 3, the instep loops *i* and the three loops *h* are shown returned to the needles.

After the restoration of loops indicated in Fig. 3, the heel tabs are turned outwardly so that loops of the fourth wale, counting from the inner selvage of the heel tabs, may be placed upon the needles, this generally being done manually. The loops of this wale are designated *l* in Fig. 2, and in order to facilitate their placement upon the needles, they are formed as large loops. Since the loops *h* and *i* are caught under the beards of their needles, and therefore cannot be dislodged during the placement of loops *l* on their needles, this operation is greatly simplified, and this constitutes an important feature of the invention. After the loops *l* have been speared on their needles, the fabric appears as in Fig. 4. The foot portion of the hose is then knit onto the fabric in the usual manner.

It has always been difficult to replace upon the needles the loops *h* which are between the instep loops *i* and the first loose loop *l*, irrespective of whether the loops *h* are only one or more in number. This difficulty has been because these particular loops *h* must be of the small size of the ordinary fabric loops, and can be found and handled only with difficulty. It is for this reason that additional points are provided on the bar 5 out beyond the ends of the series of instep points to receive the three loops at each end of the series of instep loops at the same time that the instep loops are received. These additional end loops *h*, by being retained upon points *6* during the time that the heel tabs are being knit, are returned to the needles along with the return of the instep loops *i*, and the difficulty heretofore experienced by hand operation is altogether eliminated.

To make it possible to receive the loops *h* from the needles without preventing the further knitting from these loops of the heel tab courses, the points *6* are brought against the side of the needle opposite from the beard. This is an important feature of the invention because the beard side of the needle is thereby left free to receive the new yarn and the needle may move against the press-bar to knit the new yarn in the ordinary manner. The presence of the points *6* on the back or beardless side of the needle does not, therefore, in any way interfere with the usual knitting operation of the machine, but does result in the reception of the instep loops *i* upon the points *6*, as well as those loops *h* at both ends of the instep row which heretofore have been difficult to handle.

In Fig. 1, the points *6* are shown against the beardless side of the needles *2*. In order that the

point *6*, when against this side of the needles, will enter the loops which are upon the needles, the lower end of each point is formed with a portion *6a* (Figs. 5 and 5a) bent toward the needle, so that it may enter an eye *2a* in the beardless side of the needle (Figs. 6, 6a, and 6c). The eye *2a* of the needle is slightly below the eye *2b* in the beard side of the needle for receiving the needle beard. Consequently, when the needle moves downwardly to draw the new thread through the loop about to be cast off the needle, the point *6*, which is moving downwardly with the needle, enters this loop about to be cast off, and this entry is assured because of the location of portion *6a* of the point in the eye *2a* of the needle. As has been stated, the points *6* remain in the loops *h* and *i* after they have been cast off the needles and during the knitting of the heel tabs, as appears from Fig. 2.

In returning the loops *h* and *i* to the needles after the heel tabs have been fully knit and cast off, the points are brought over the tops of needles and against their beard side, and this final relationship is shown in Fig. 3. To assure registration between the point and the needle, so that this redelivery may be effected, the point is formed with a recess *6b* (Figs. 5, 5a, and 5c) which will receive the beard of the needle. At the upper portion of the recess *6b*, the side walls are of increased width, so that the recess is deeper at this portion to more fully receive the needle beard.

The actual steps by which the loops are received from the needles, and thereafter are returned to the needles, is illustrated in Figs. 7 to 17, and Figs. 8a to 12a. The figures bearing the letter *a* show a needle in the same position as a needle in the correspondingly numbered figure, with the difference that the figures not having this letter show a needle at the instep portion of the fabric, while the figures having this letter show a needle at the heel tab portion of the fabric. Thus, in Fig. 8 is shown a needle having one of the instep loops *i* of Fig. 1, while in Fig. 8a is shown a needle having one of the heel tab foundation loops *h* of Fig. 1. Both the needle of Fig. 8 and the needle of Fig. 8a are in the identical part of their paths of movement.

In Fig. 7 the needle *2* has risen through its instep loop *i* to the position at which a new yarn would be received. Shortly before the needle reached this position, the frame *1*, which is ordinarily in an upper position shown in full lines in Fig. 18, was swung downwardly about its pivot *12* to the dotted line position shown in Fig. 18. This brings the instep points *6* to a position spaced from the beardless side of the needle, as shown in Figs. 18 and 7. Since the loop *i* is an instep loop and is in the last course before the heel tabs are knit, a new thread is not fed to the needle having this loop *i*. The thread finger *3* appearing in Fig. 7 is the one which, at this time, is feeding a new yarn *y* to the needles which will knit one of the heel tabs from the loops *h*.

In Fig. 7 and the subsequent figures which show the steps by which the loops are received upon the points *6* from the needles *2*, the needle is moving through its regular knitting path. This is an important feature of the invention made possible by the fact that point *6* is on the beardless side of the needle during the time that it receives the loop from the needle. It is not necessary, therefore, to cause the machine to go through a portion of its narrowing motion, as has been the usual practice, when the loops are

bodily transferred from the needles to the points. The machine performs its regular knitting motion to cast off the loop thereon, but because the loop is on a point 6, the loop remains upon or is received by the point.

In Figs. 8 and 8a the needles have moved downwardly so that the new yarns fed to the needles for the heel tabs have nearly entered the hooks formed by the beards of the needle. One of the yarns *y* appears in Fig. 8a. The points 6, which by this time have moved against the needles with their bent portions 6a within the eyes 2a of the needles, are moving downwardly with the needles and their lower ends are about to enter the loops *i* and *h* upon the needles.

In Figs. 9 and 9a the points and needles have moved further downwardly, so that the points 6 have entered the loops on the needles. In these figures, the needles have also moved toward the presser bar from their position in Figs. 8 and 8a. In Fig. 9a the new yarn *y* is now within the beard of the needle.

In Figs. 10 and 10a the needles are against the presser bar 3a to close the beard and the needles are moving downwardly through the loops *h* and *i* so as to cast them off. The points 6 are now well within these loops which will be cast off. In Fig. 10a the new yarn *y* is about to be drawn through the loop *h* which is to be cast off.

In Figs. 11 and 11a the needles have moved downwardly far enough to cast off the loops *h* and *i*. It is not necessary to move the points down from their position in Figs. 10 and 10a, since the lower ends of the points are below the tops of the knock-over bits 4, and the fabric therefore cannot drop off of the points. The points 6 having thus remained in the loops, the reception of the loops upon the points from the needles is now completed. In Fig. 11a the new yarn *y* has been drawn through the cast off loop *h* and the new loop so formed is within the beard of the needle. In Fig. 11 there is no such new loop upon the needle, because no yarn was fed to the instep needles, and the instep loops *i* are therefore entirely free of the needles. Since the needles are going through their regular knitting motion in Figs. 11 and 11a, they have moved away from the presser bar. It is necessary that the points 6 likewise have moved away from the presser bar, as appears in these figures.

From the positions in Figs. 11 and 11a, the needles continue to go through their regular knitting cycles in order to knit the several courses of the heel tabs. The fabric is drawn away from the needles by the combined action of the usual take-up means and by means herein-after described, so that after several courses have been knit, the points are spaced from the needles as shown in Figs. 12 and 12a. In Fig. 12a the heel tab courses are shown between the needle 2 and the loop *h* on the point 6. To retain the loops *h* and *i* upon the points while the heel tabs are knit, the knock-over bits 4 in this region of the fabric are elongated to form extensions 4b lying between the points, as appears in Figs. 12 and 12a. For this reason, the lower ends of the points are maintained at or near the low level at which they receive the loops. During the knitting of these heel tabs, narrowing may be performed as required.

Fig. 13 shows the return of the points 6 toward the needles after the heel tabs are completed and have been dropped off the needles. The return of the heel tab loops *h* is the same as the return of the instep loops *i*, and Fig. 13 and the subse-

quent figures, showing the steps in the transfer of the loops *i* from the points back to the needles, apply to the loops *h* as well. In Fig. 13 the needle is starting to pass through the last half of the ordinary needle narrowing motion, the cam shaft having been shogged to cause this to occur. The needles and narrowing frame have just passed through the first half of the narrowing motion, but this is merely an idle movement as there are no loops on the needles.

In Fig. 14, the point is passing over the top of the needle to reach the beard side thereof, and in Fig. 15 the point is lowered on the beard side of the needle. The point has been lowered enough in Fig. 15 so that the fabric is brought upon the knock-over bits 4. This permits the sinkers 3b to move over the fabric when they are advanced, the sinkers being partly so advanced in Fig. 15.

In Fig. 16 the point and needle have been brought together so that the beard of the needle lies in the eye 6b of the point 6. Upward movement of the needle and of the point will cause the needle to enter the loop of the fabric, and will cause the point to withdraw from the loop, due to the fact that the fabric is being held down by the sinker 3b. This relation is shown in Fig. 17, from which it appears that the transfer of the loop from the point to the needle has been completed, the loop *i* being upon the same needle it was on in Fig. 7. In like manner, the three loops *h* at each end of the instep loops are again upon their original needles.

After the heel tabs have been then turned outwardly and the large wale of loops *l* speared on the needles as shown in Fig. 4, the foot portion of the fabric may then be knitted in the usual manner. The points 6 may be removed from their location in Fig. 17 by turning the frame 7 upwardly about its pivot 12 so that bar 5 is held by clamp 19 (Fig. 18).

The frame 7 remains in its upward position during the knitting of the foot portion of the fabric, and also during the knitting of the leg portion of the next fabric until it is required to be lowered to receive the loops of the last course of the new fabric before the heel tabs. To cause the frame to become disengaged from clamp 19 and be lowered automatically at the proper time, it is given a forward movement by the upper end of an arm 20 which is brought against the frame 7 (Figs. 18, 19, 20). The arm 20 is secured to a rock shaft 21 rotatably supported in the upright arms 22 secured to a fixed bar 23 of the machine framework. Also fixed to rock shaft 21 is an arm 24 which is connected by a link 25 to one arm 26 of a bell crank lever pivoted upon an upright 28 of the machine framework. The other arm 27 of the bell crank lever is connected by link 29 to a lever 30 pivoted to the machine framework. The free end of lever 30 is formed with a projection 31 which lies in the path of movement of a lug 32 on the side of a plate on control shaft *b*. Control shaft *b* is the shaft *b* of the machine disclosed in the Howie et al. Patent 1,982,991, issued December 4, 1934, being there designated as a yarn changer shaft. A spring 33 acts to withdraw the arm 20 from the frame 7, and also to urge the end 31 of lever 30 into the path of lug 32.

At an appropriate time shortly before the course containing the loops *h* and *i* is knit, and preferably during the knitting of the high splice of the heel, the lug 32 acts to cause the arm 20 to kick the frame 7 forward sufficiently for it to turn by gravity downwardly about pivot 12. The

frame 7 is caused to descend slowly by the provision of a suction piston 34 and cylinder 35 (Figs. 19 and 20). The cylinder 35 is pivoted at its upper closed end in any suitable manner to the upper ends of uprights 36. These uprights 36 are secured to a cross bar 37 fixed between the arms 11 which provide the pivot points 12 at their forward ends about which the frame 7 turns. The connecting member 38 of the piston 34 is pivoted to a pin 39 which projects from a block 40 secured to the cross bar 13 fixed in frame 7. The member 38 is wide enough to bear against the cylinder wall and serve as a guide for the piston in and out of the cylinder. The lower part of member 38 is cut away to receive the cross bar 13, as appears in Fig. 20.

When the frame 7 is in its upper position, the piston 34 is furthermost within the cylinder 35. Downward movement of the frame 7 causes the piston to move outwardly of the cylinder, and this is resisted by the suction created within the cylinder. When the frame 7 has nearly reached its lowermost point, the piston passes beyond a port opening 41 in the side of the cylinder 35. This releases the suction above the piston and allows the frame 7 to fall rapidly during the last portion of its downward movement.

Such final rapid motion of the frame 7 gives the frame sufficient momentum to cause an inclined surface 42 (Fig. 21) on the side of the frame 7 to force inwardly a pin 43 which is pressed outwardly of a slide bar 45 by a spring 46. The pin 43 in this manner is brought into the cam groove 51 formed in block 52 secured to one of the arms of frame 7. Through the connection so established, back and forth movement imparted to the slide bar 45 causes the frame 7 to swing about its pivot 12, so that the points 6 move back and forth in a horizontal direction.

Slide bar 45 is supported and guided by faces 53 (Fig. 20) which bear on the top and bottom flat sides thereof, and by a rod extension 54 thereof which may reciprocate in a bore hole 55. The guide faces 53 and bore hole 55 are formed in a lower forward extension 14 of one of the arms 9 affixed to cross rod 8 of the narrowing frame 47. To reciprocate the slide bar 45, an arm 56 (Figs. 20, 21) projecting therefrom carries a pin 57 which enters a cam groove 58, 58' (Fig. 24), formed on the side of a cam plate 59 by affixed cam pieces 61 and 62 and central cam piece 63. To limit outward movement of the slide bar 45 and prevent movement of pin 57 from the cam groove 58, 58', a pin 64 projecting from the side of arm 56 is located to strike the pin 65 secured in part 14 (Figs. 20, 21).

The cam plate 59 is secured to an auxiliary cam shaft c rotatably supported in bearings of both arms 9. Rotation of shaft c a half turn will cause the portion 58 of the cam groove to draw the frame 7 toward the needles from the initial position, shown in Figs. 7 and 20, which it and the points 6 assume after the downward movement of the frame. This half turn rotation of shaft c occurs as one complete motion, by means which will be described, during the time that the needle is going through the portion of its knitting cycle in which the new yarn is drawn through the loop being cast off the needle.

To impart the necessary vertical motion to points 6 relative to the narrowing frame 47, a cam 67 (Fig. 23) is secured to cam shaft c. Upon the periphery of cam 67 bears a roller 68 (Figs. 20, 21) supported upon the side of a link 69 which, at its upper end, is pivotally connected to one of

the arms 11 adjacent the cross bar 37. The lower end of link 69 is slotted to receive the reduced end 70 of shaft c, and in this manner maintain the roller 68 upon the cam. Rotation of shaft c will move the arms 11 up and down about the shaft 10 to which they are affixed. Shaft 10 is pivotally mounted in the upper ends of arms 9 of the narrowing frame.

To draw the arms 11 downwardly and maintain roller 68 upon the periphery of cam 67, an arm 71 (Fig. 20a) is affixed to shaft 10 centrally of the machine, and a spring 15 is connected to this arm. The lower end of spring 15 is anchored to the guard 16 which receives the narrowing knife 17 when not in use. These latter parts form no part of the present invention, but it may be mentioned that the knife 17 is pivotally mounted upon a central cylindrical portion of screw shaft 46b which drives the narrowing rods 44 carrying the narrowing combs (not shown). A cam 18 on the picot bar shaft 50 acts upon arm 17a to lift up the knife when the picot bar is swung down.

Since the frame 7 is entirely supported and operated by parts associated with the narrowing frame 47, including pivot shaft 10 for arms 11 and slide bar 45 and its connections, the frame 7 must partake of every motion of the narrowing frame, unless prevented by means to be herein-after described. During the period that the loops are received upon the points from the needles, since this is accomplished during a portion of the regular knitting motion, the narrowing frame is not in motion and the movement of the frame 7 is solely that which is imparted to it by cams 59 and 67. However, during the return transfer of the loops from the points to the needles, since this is accomplished during a portion of the ordinary narrowing motion when the narrowing frame 47 is in operation, the frame 7 has the same motion as that of the narrowing frame.

To accomplish this transfer of the loops from the points to the needles, the cam shaft c is first moved through half a turn, this being the second half of its revolution, and this brings the points 6 over the tops of the needles to their bearded side and in such relation to the narrowing frame 27 that the narrowing frame in then going through its regular motion will deliver the loops from the points to the needles. During this delivery action the cam shaft c remains at rest, the entire movement of the frame 7 being that which it receives by being carried by the narrowing frame. In returning the loops to the needles, the narrowing frame passes through its full cycle, but the first half of this cycle is an idle operation, it being the second half of this cycle which actually accomplishes the transfer of the loops from the points to the needles.

To cause rotation of cam shaft c, it is driven at its end opposite from cams 59 and 67, by a gear 72 (Figs. 22 and 25) rotatably mounted upon a projection 74 of cross rod 8 beyond the side of the narrowing frame. The gear 73 on shaft c is half the size of gear 72, so that shaft c will turn at twice the speed of gear 72. Gear 72 is advanced by means of a ratchet 75 affixed thereto and a pawl 76 pivoted at 77 to a plate 78, which is also rotatably mounted upon the projection 74. A spring 79 connected to plate 78 urges the pawl 76 against ratchet 75. The plate 78 is oscillated about projection 74 by pull upon a link 80 pivotally connected to the plate 78 at 81.

There are only four equally spaced notches 82

in ratchet 75, and each oscillation of plate 78 under the action of link 80 must be sufficient in extent to advance the pawl 76, and thereby the ratchet 75, a quarter turn, and then return the pawl so that it will engage the next notch 82. The quarter turn so given to the gear 72 rotates gear 73 and shaft c a full half turn. Each time that a pull is exerted upon link 80, therefore, the cams 59 and 67 pass through a complete half turn to cause frame 7 to go through a continuous motion either preliminary to the reception of the loops upon points 6 or preliminary to the transfer of the loops from the points back to the needles. To retain gear 72 in each of its quarter turn positions, a plate 83 having four quarter-turn spaced notches 84 is affixed on the outer face thereof, and a spring pressed detent 85 engages in the notches 84. The detent 85 and the adjacent end of shaft c are supported by arm 86 secured to cross rod 8. To prevent over travel of cam shaft c, it is provided with a brake drum 87 upon which constantly bears a brake shoe 87' supported by cross bar 8.

Pull is exerted upon link 80 by its pivotal connection at 88 to a plate 89 loosely rotatable upon control shaft b. Also pivoted to plate 89 at 90 is a hanging link 91 having at its lower end a shoulder 92. To press upon shoulder 92 and draw the link 91 downwardly, a lever 93 is provided with a pin 94 projecting laterally therefrom, and which the shoulder 92 may underlie. Normally, however, the link 91 is held away, so that there will be no engagement between pin 94 and shoulder 92, by a pin 95 of a lever 96 pivoted at 97 to the machine framework.

Where the lever 96 passes control shaft b, it is provided with a lateral lug 98 which bears upon the periphery of a circular plate 99 affixed to the control shaft. A spring 100 connected to link 91 exerts a pull on this link, which, through its contact with the pin 95, draws lug 98 against plate 99. Plate 99 is formed with notches 101 which, when brought opposite lug 98 by the rotation of control shaft b, allow the lever 96 to swing so as to withdraw the pin 95 at the lower end thereof away from the link 91. This allows link 91 to move toward the bell crank lever 93 under the action of spring 100, so that shoulder 92 of the link 91 will lie under pin 94 of lever 93. One of the notches 101 comes into registry with lug 98 at the moment the loops are to be received upon the needles, and the other notch comes into registry at the moment the loops are to be transferred back to the needles.

The lever 93 is affixed to a hub 132 which is oscillated about its pivot bolt 131 to cause pin 94 to draw link 91 downwardly, by one of the cams 102 and 103 upon the main cam shaft a, one of these cams being brought to act on the roller 104 carried by another arm extending from hub 132. During the step of receiving the loops upon the points from the needles, this being accomplished while the needle is passing through a portion of its knitting motion, the cam 102 is beneath the roller 104 to give the lever 93 the necessary motion. When the loops are being transferred from the points to the needles, since this is accomplished during a portion of the needle narrowing motion and the main cam shaft a has therefore been shogged endwise in the usual manner, the roller 104 rides upon cam 103 and this gives the required motion to lever 93.

It will be evident that the lever 93 is constantly in motion, since its roller 104 is being

operated either by cam 102 or cam 103. This constant motion, however, is not transmitted to link 91 until the moment that one of the notches 101 is in position to allow the shoulder 92 of link 91 to move inwardly under pin 94. Inasmuch as shaft b does not make an immediate turn to break the connection between shoulder 92 and pin 94, it is evident that the downward pull on link 91 would be repeated and shaft c would consequently make more than the desired single half turn, if means were not present to prevent this. This means includes a detent 105 which is pivoted upon pin 88 and rides upon the periphery of plate 89. When one of the notches 101 comes into registry with lug 98 and plate 89 is rotated counterclockwise to the position shown in Fig. 25a, the detent 105 drops into a small notch 101' in the periphery of plate 89, and prevents return motion of plate 89 in a clockwise direction under the influence of spring 100. The lever 93 therefore merely moves idly and repeated actuation of shaft c is prevented.

This idle movement of lever 93 is maintained while plate 89 is advanced clockwise by shaft b to which it is connected. Such movement of plate 89 also forces lug 98 out of its notch 101 and carries shoulder 92 out of the range of pin 94. Thereafter the link 91 will not be actuated and shaft c will not be turned until the other one of the notches 101 comes into registry with lug 98. When this occurs, the first notch 101 will be in such position that the detent 105 will drop into it when plate 89 is rotated counterclockwise and will prevent repeated movements of shaft c.

As has been noted, the half turn rotation of cam shaft c which occurs after the frame 7 has descended, brings the points 6 inwardly toward the needles from the position of Fig. 7 to the position of Fig. 8, and further moves the points through the steps shown in Figs. 9, 10, and 11. Thereafter regular knitting of the heel tabs is performed. During this knitting of the heel tabs, it is desirable that the points 6 move back and forth with the needles as the needles move toward and away from the press, in order to reduce the stress which otherwise would be placed upon the heel tab loops, if these loops were alone relied upon to move the points. To cause the points to so move with the needles, in accordance with the invention, a lever 106 (Figs. 19, 25, 27 to 31, inclusive) is provided which establishes a connection between the needle bar and the frame 7.

This lever 106 is fulcrumed at its center to a pin 107 projecting from an angle plate 108, which, in turn, is pivoted by pin 109 to an arm 110 extending from the side of the frame 7. A leaf spring 109' acts to turn lever 106 about pin 109 in a clockwise direction in Fig. 19 to bring plate 108 against shoulder 110' of arm 110, which acts as a stop. At its lower end the lever 106 has a laterally extending portion 111 (Fig. 27a) which is formed with a notch 112 and an inclined face 113. When the frame 7 is drawn toward the needles by the action of cam 59 (Fig. 20), the inclined face 113 is brought against a cam ridge 114 of a plate 115 (Figs. 19, 27, and 31) secured to the needle bar, and the lever 106 is thereby forced aside about the pin 109 so that the notch 112 embraces the cam ridge 114.

To prevent the points 6 from swinging in and striking the needles, if this should inadvertently tend to occur because of failure of the engage-

ment between cam ridge 114 and notch 112, a stop 119 is provided. This stop limits the inward movement of the lower end of lever 106 and thereby the points 6.

The upper end of the lever 106 is held against motion at the time the inclined face 141 strikes cam 114 by a pin 116 on the side of lever 106, which projects into a recessed portion 117 of a cam 118 (Fig. 29). In this manner, the lever 106 is held in fixed relation to the frame 7, so that the notch 112 at the lower end of the lever will be forced into place upon the cam ridge 114.

The cam ridge 114 has the shape shown in Figs. 27 and 31 in order to cause the points 6 to more exactly follow the movements of the needle bar. This provision is desirable because the needle bar does not move up and down and back and forth in purely rectilinear paths, but, on the contrary, these motions are due to movements of the needle bar about pivot points as shown in Fig. 5 of the aforementioned Howie et al. patent. As the needle bar passes through these motions the relative movement of the notch 112 along the cam ridge 114 compensates for the pivotal mounting of the needle bar and causes the points 6 to have nearly the exact back and forth motion of the needle bar so that stress is not imposed upon the first few courses of the heel tabs.

The cam 118 is secured to the side of a ratchet wheel 120, which is rotatable upon a pin 121 projecting from the side of a bracket 122 secured to one of the arms 11. Cam 118 is so shaped that upon its rotation by ratchet wheel 120, the upper end of lever 106 will be forced forwardly away from the machine. During this action, the lever 106 will turn about its lower end as a pivot, and will thereby move the frame arms 7 forwardly so as to move points 6 away from the needles. Such forward movement of points 6 occurs at the same rate that the heel tabs are knit, so that a take-up of the heel tab fabric is provided for at least a few of the first courses.

To rotate the ratchet 120, and thereby cam 118, a pawl 123 is provided (Figs. 18, 25, 28). The pawl 123 is pivoted to an arm 124 secured to a sleeve 125 which is rotatable upon the fixed cross bar 23 of the machine frame. Also affixed to sleeve 125 is an arm 126 to which is pivotally connected a link 127, the other end of this link being pinned to a bell crank lever 128 pivoted to the machine frame. From the other arm of the bell crank lever 128, a link 129 extends to an arm 130 projecting from the hub 132. Oscillation of hub 132 by roller 104 causes oscillation of arm 130. The cams 102 and 103 thus also serve to actuate pawl 123 for rotating ratchet 120, and since the roller 104 is constantly acted upon by one of these cams, the ratchet 120 and cam 118, 60 may be moved step by step.

Normally, the pawl 123 does not rotate ratchet 120, because the ratchet has a blank space 133 in which the tooth 134 of the pawl 123 moves. Support 123' may be provided for pawl 123 to prevent wear upon tooth 134 during such idle movement. When, however, the arms 11 are lowered by the action of cam 67 at the time the points are to receive the loops from the needles, the tooth 135 at the outer end of pawl 123 comes in contact with a tooth of the ratchet 120 and starts its rotation. Thereafter the ratchet will be rotated either by tooth 134 or 135 until a complete rotation has been accomplished, at which time the blank space 133 of the ratchet 75

will again come beneath tooth 134 and the ratchet will remain at rest. Such a complete rotation of cam 118 preferably occurs before the entire heel tab is knit. Thus, the cam 118 acts to move the points away from the needles during only the first several courses of the heel tabs to take up the knit fabric. Thereafter, the fabric which is knit may lie loose between the points and the needles.

10 It has been stated that initially the pin 116 of lever 106 is in the recess 117 of cam 118. Rotation of cam 118 being clockwise, looking at Fig. 29, the pin 116 is moved away from the axis of cam 118 by the periphery of this cam until an inclined face 141 on a projecting part of cam 118 reaches pin 116. This inclined face 141 forces the upper end of lever 106 aside and places pin 116 upon the ledge or shoulder 141' on the side of the cam 118. During the knitting of the final 20 part of the heel tabs the pin 116 remains upon this shoulder 141'. The shoulder 141' is elongated so that the pin 116 may move along it during the narrowing operations. Incline 141 also disconnects notch 112 from cam 114.

25 The pin 116 should be upon the shoulder 141' before the heel tab narrowings are commenced. That is, the cam 118 should have completed its rotation by this time and tooth 135 should be moving idly in space 133 of ratchet 120. To prevent a false movement of ratchet 120 at the time 30 heel tab narrowings are being made, a lever 136 (Figs. 27, 31, 32, 33) is provided. This lever is pivoted upon shaft 23, and has an affixed projection 137 which may strike pawl 123 so as to 35 prevent a false movement of ratchet 120, as in Fig. 31. A coiled spring 138 tends to swing lever 136 to lift pawl 123, but this is normally resisted by the contact of the lower end of lever 136 against the cross bar 8 of the narrowing frame 47. Descent 40 of the narrowing frame withdraws bar 8 from lever 136, so that the lever swings outwardly and acts to lift pawl 123. When the narrowing frame then rises, the pawl 123 cannot engage ratchet 120 to rotate it, as would occur if lever 136 were not provided. Also, when the narrowing frame rises the lower end of lever 136 is carried to the rear of cross rod 8 as shown in Fig. 27, by the guiding action resulting from the contact of lever 136 against the pivot bar shield 136'.

45 In addition to the progressive motion of points 6 away from the needles to take up the fabric of the heel tabs as they are knit, it will be clear that the points follow the back and forth motion of the needles as the needles move to and away from the press bar 3a, this latter result being achieved by the presence of lever 106. Movement of the needle bar to and away from press 50 swings the lower end of lever 106 about the pin 116 at its upper end as a pivot, and through the connection at 107 the arms 7 are actuated to correspondingly move the points 6 with the needles. By causing the points to move with the needles in this manner, the loops and the fabric between the needles and the points are not stressed. If this connection were not provided, the force required to move the points with the needles would be placed entirely upon the few loops between the needles and the three heel tab 55 foundation points beyond the ends of the instep point row.

55 The movement of frame 7 and points 6 away from the needles under the action of cam 118 is not restrained by cam 59, because during this time the cam 59 is in such position that one of the gaps between the ends of cam pieces 61 and

62 (Fig. 24) is in line with the motion of pin 57 outwardly away from cam 59. Thus the outward movement of frame 7, caused by cam 118, carries with it the slide member 45 due to the engagement of pin 43 in cam groove 51, and since lower pin 57 is connected to the slide member 45, it is moved away from the axis of shaft c without interference, due to the space between the ends of cam pieces 61 and 62.

Narrowing of the heel tabs may be performed with the present apparatus in the usual manner. For this purpose narrowing combs (not shown) may be secured to the slide bars 44 and receive their movements along the needle row from the screw shaft 46b. The up and down motion of the narrowing frame is derived from links 46 (Fig. 25) which are connected at their upper ends to arms secured to shaft 8 of the narrowing frame, and are connected at their lower ends to the levers 48 which are secured to a shaft 49. Suitable cams (not shown) on the main cam shaft serve to rock the shaft 49 and thereby actuate the narrowing frame.

Inasmuch as the narrowing frame 47, when performing the heel tab narrowings, is swinging up and down, and thereby would tend to carry the frame 7 with it, the invention provides means to hold the hanging frame 7 upwardly during the narrowing operation and prevent the points 6 from descending and striking some part of the machine. For this purpose a curved arm 185 is loosely pivoted upon the shaft 10 to which the arms 11 are secured. The upper part of arm 185 has a curved inner face 186, which is urged against the fixed cross rod 23 by a coiled spring (not shown) surrounding shaft 10 within the hub portion of lever 185. Up and down movement of the narrowing frame when the instep loops *i* and end loops *h* are being returned to the needles causes the face 186 to ride along rod 23, but this serves merely to turn the arm 185 about rod 10, since the arm is loose thereon. However, when heel tab narrowings are being performed the arm 185 is connected to the shaft 10, so that as the narrowing frame descends, the movement of the curved face 186 along the rod 23 will serve to turn shaft 10. The face 186 is so shaped as to cause the shaft 10 to turn the proper amount to elevate the arms 11 and thereby constantly maintain the pivot 12 for arms 7 in nearly the same position.

This connection which is established between the arm 185 and shaft 10 includes an arm 187 which is pinned or otherwise secured to the shaft 10. An opening 188 is formed in arm 187 and into this opening extends a pin 189 projecting from the side of a plate 190 freely pivoted upon shaft 10 between arms 185 and 187. The opening 188 is considerably larger than the pin 189 and to hold the pin in fixed relation within the opening, oppositely disposed screws 191 extend into the opening 188. Adjustment of these screws 191 will vary the angular relation between the arm 187 and the plate 190 about shaft 10.

Engagement between the arm 185 and the plate 190 is established as desired by a pin 192 located in the arm 185. This pin 192 may be urged outwardly of the arm 185 so as to lie in front of a face 193 of plate 190. When the pin 192 is in front of the face 193 of plate 190, it is apparent that the turning movement of arm 185 due to its action against rod 23 will cause the pin 192 to bear against the face 193 of plate 190 and cause the plate to turn about the axis of shaft 10. This

turning of plate 190 will carry with it the arm 187 due to the projection of its pin into the opening of arm 187, and since the arm 187 is pinned to shaft 10, this shaft will be turned and the arms 11 will be lifted to maintain the pivot 12 in an upper position.

The pin 192 is normally urged within the arm 185, so that it will not strike the face 193 of plate 190 by a spring 194. To urge the pin outwardly, it is acted upon by a cam face 196 on a lever 197 which is loosely pivoted upon shaft 10. A collar 198 secured to shaft 10 retains the lever 197 against the side face of the hub of arm 185. The free end of lever 195 extends into the path of a cam 199 on the cam shaft c. When the lever 197 is upon the low part of cam 199, the low part of the cam face 196 is in front of pin 192 so that the pin will be retracted under the action of spring 194. When the lever 197 is upon the high part of cam face 196, this being when the heel tabs are being knit, the high part of the cam face 196 will be in front of the pin so that it will be urged before the face 193. Therefore, during heel tab narrowing the hanging frame will be held up to the same position it assumes during the knitting of the heel tabs.

It is for the purpose of further insuring that the points 6 of the frame 7 will remain in nearly a fixed position during the performance of the heel tab narrowings that the cam groove 51 is provided. Due to the shape of this cam groove, when the frame 7 is being held up by the action of arm 185, the swinging movement of slide bar 45 due to its being carried with the narrowing frame does not exert a pushing action upon frame 7. Instead, the pin 43 merely moves back and forth along the cam groove 51 and exerts no swinging action upon the frame 7. Therefore, due to the combined action of arm 185 and the cam groove 51, the points 6 remain in nearly a fixed position despite the fact that the narrowing frame to which it is connected is in motion.

Since after the heel tabs have been completed and cast off, and after the loops *h* and *i* have been returned to the needles, the loops lying in the wale *h* near the inner edge of each tab are to be speared upon needles so that the foot portion of the fabric may be knit from them, means are provided to make these wale loops exceptionally large to facilitate this spearing operation. For this purpose, the enlarging points disclosed and claimed in application Serial No. 184,329 of Kenneth Howie, filed on January 10, 1938, now Patent No. 2,190,665, are employed, but in accordance with the present invention, these enlarging points are brought into operation and placed out of operation automatically.

The two enlarging points 142 (Fig. 19) are secured in blocks 143 affixed to a rock shaft 144, which is rotatable in bearings 145 carried by the needle bar. Normally the rock shaft 144 is in the position shown in Figs. 18 and 19, so that the points 142 are away from the needles, and therefore inoperative. Rotation of the rock shaft will bring the two points 142 against the two needles which are to form the enlarged loops of the heel tab wales, as shown in Fig. 20. The extreme ends of the points 142 enter the eyes 2a of the needles, so that the points will freely enter the loops upon the needles as the needles and points move upwardly.

The wale of large loops in one of the heel tabs is shown at *l* in Fig. 2. It will be observed that the needle forming these loops *l* is the one next to the needle from which the end point 6 receives

its loop. Thus, if, as here shown, the points receive loops from three needles of the heel tabs, counting from their inner selvage edges, one of the enlarging points 142 contacts the fourth needle from that selvage edge. As shown in Fig. 4, it is these large loops *l* which are speared on the needles after the loops on the points are returned to the needles, and the heel tabs are turned outwardly.

A coiled spring 146 encircling rock shaft 144 tends to rotate the shaft to bring the points against the needles. Rotation of the rock shaft 144 is controlled by a gear 147 affixed thereto and meshing with the teeth of a gear sector 148 pivoted at 149 to the needle bar. To prevent rotation of gear section 148 a bell crank lever 150 pivoted at 151 to the needle bar provides a stop shoulder 152 against which a corner of the gear section 148 bears. A coiled spring 153 tends to turn the lever 150 to retain its shoulder 152 against the gear sector and thereby maintain the enlarging points away from the needles.

To remove shoulder 152 from the gear sector 148 at the proper time, a member 154 is brought in position to be struck by arm 155 of the bell crank lever 150 to turn the lever about its pivot at 151. The member 154 is secured to a link 156 ordinarily present upon the machine and which, at its rear end, is pivotally connected to one arm of a bell crank lever 157 (Fig. 18) pivoted to the machine framework. The other arm of bell crank lever 157 is formed with a projection 158 disposed to be contacted by a lug 159 of a member on the control shaft *b*. The forward end of link 156 may be thrust into engagement with the ratchet 160 of the fabric take-up drum to stop its rotation when the heel tabs are being knit. This prevents the full pull of the take-up from being exerted upon the narrow heel tabs.

During normal operation, the member 154 is 40 out of the path of movement of arm 155, the arm 155 having the same movement as the needle bar. When member 154 is thrust into the path of movement of arm 155, under the influence of lug 159, the lever 150 is tripped and the sector 148 and rock shaft 144 are rotated to bring the enlarged points 142 against their needles. The lever 150 is tripped in this manner at such an instant that the enlarging points will be in position against the needles to form large loops in the first course of the heel tabs. Thus the enlarging points 142 come into position at the time the points 6 received the instep loops *i* and loops *h* at the base of the heel tabs.

The enlarging points 142 remain against the needles throughout the knitting of the heel tabs. To automatically withdraw the enlarging points from the needles and return them to their inoperative position after this time, the gear section 148 is provided with a depending arm 161 from which projects a pin 162 for engagement with a shoulder 163 of a link 164. During the knitting of the heel tabs, the descent of the needle bar brings the pin 162 into a position in front of and close to the shoulder 163, but no movement is imparted to pin 162. At the time the enlarging points are to be withdrawn from the needles, the link 164 is drawn forwardly so that its shoulder 163 will be in the path of movement of pin 162.

The force so exerted on pin 162 as it moves against shoulder 163 serves to turn the gear sector 148 until the shoulder 163 on lever 150 moves inwardly thereunder due to the influence of spring 153 and locks the gear sector in idle 75

position. The rock shaft 144 is thereby rotated to move the enlarging points to their inoperative position.

The forward movement of link 164 to turn gear sector 148 is caused by its pivotal connection to an arm 165 secured to a sleeve 166 which is rotatable upon a fixed rod 167 of the machine framework. Another arm 168 affixed to the sleeve 166 is connected by a link 169 to a rock lever 170 which is pressed toward the pattern drum A by a spring 171. A lug 172 is so located upon the pattern drum that it will strike and raise rock lever 170 at the proper time to draw link 164 forward. Link 164 is supported upon a shaft 173 of the machine, upon which the link slides when actuated by the lug 172 of the pattern drum.

It has been pointed out that shortly before the points 6 are to receive the loops from certain of the needles, the frame 7 is kicked forward from its upward position by movement of arm 20. As a safety measure, to prevent the frame 7 from moving downwardly if cam 118 is inadvertently in an incorrect position at this time, the invention provides means for holding the frame upwardly against the influence of arm 20. For this purpose, one of the arms of frame 7 is provided with a lug 175 (Figs. 19, 27) which may be engaged by a shoulder 176 of a block 178 affixed on the side of a lever 177, when the lever is moved upwardly to bring the shoulder 176 in front of lug 175. Lever 177 is pivoted upon the cross rod 37 which connects the arms 11.

To operate lever 177, its forward end bears upon a cam 179 secured to the side of ratchet wheel 120 opposite from cam 118. Cam 179 has a flat peripheral portion 180 which allows the lever 177 to drop to a position such that the block 178 will be below the arc of travel of lug 175, and therefore the shoulder 176 will not be contacted by the lug 175 as the frame 7 moves to downward position. This is the position which the cam 179 should assume when it is kicked forward by arm 20. If the cam is in some other position due to the fact that cam 118 and ratchet 120 are wrongly positioned, the lever 177 will be raised so that its shoulder 176 will lie in the path of movement of lug 175 and prevent forward movement of the frame 7. In this event, the operator manually turns the ratchet 120 to bring the flat or low point 180 of cam 179 under the lever 177.

A detent 181 (Figs. 31, 32) permits rotation of ratchet 120 in one direction only. Stop pins 182 limit rotation of lever 177 about cross rod 37, to make certain that the lever 177 rests upon the periphery of cam 179. A recess 183 is formed in cam 179 just forward of the flat face 180, for the tip end of lever 177 to enter during the heel tab narrowings as this position tends in effect to give a reverse motion to cam 179. It is at the times that the tip end of lever 177 enters recess 183 that the pin 116 of lever 107 rides upon the ledge or shoulder 141.

After the heel tabs have been completely knit and have been cast off the needles, the loops on the points 6 are returned to the same needles from which they were removed by the joint action of a half turn rotation of auxiliary cam shaft *c* and the second half of the regular needle narrowing motion. The half turn rotation of auxiliary cam shaft *c* brings the points 6 over the tops of the needles to their beard side and into line with the narrowing points on the machine. To assure such alignment, the frame

7 is provided with stops 201 which bear against the forward one of the narrowing bars 44. The machine in then passing through the second half of its narrowing motion delivers the loops *h* and *i* to the needles.

During this delivery operation, it is desirable to make certain that the narrowing combs are not moved inwardly the usual two needle spaces. Such disconnection is effected by a cam *c*⁵ upon the auxiliary cam shaft *c*. A lobe 203 of cam *c*⁵ acts to lift arm 204 affixed to a shutter control shaft 205 at the time that the screw shaft 44b is about to be turned to move the narrowing combs inwardly. A spring 206 encircling the shaft 205 turns the arm 204 against cam *c*⁵. Also affixed to shaft 205 is an arm 207 which, when shaft 205 is turned by cam *c*⁵, acts to move into shielding position the shutter 208. In this position, the shutter 208 lies between the driving pawl (not shown) which actuates ratchet 209 and thereby nullifies the movement of the driving pawl. The parts 208 and 209 are 44f and 44g respectively in the aforementioned Howie et al. patent, which may be referred to for a detailed disclosure of them and the related mechanism.

The loops *h* and *i* now being upon the needles, the machine automatically comes to rest so that the heel tabs may be turned outwardly by hand and the large wale loops *l* of each heel tab be manually speared upon the needles. Thereafter the machine is started and the usual foot portion of the hose is knit onto the fabric. The hanging frame 7 should be swung up to be caught by clamp 19 as soon as the transfer of loops back to the needles is accomplished.

I claim:

1. The method of knitting a complete hose fabric upon a flat full fashioned machine which comprises locating loop receiving points on the beardless sides of the needles from which loops are to be received, and operating the needles through a knitting cycle so that the loops will be cast off the needles by the usual pressing operation of the knitting cycle and be received by the points.

2. The method of knitting a complete hose fabric upon a flat full fashioned machine by ceasing knitting at the instep while the heel tabs are knit, which comprises receiving upon points, loops which are cast off of the needles by the usual pressing operation during a knitting cycle, said loops being in the course before the heel tabs are knit, retaining the loops so received upon the points while the heel tabs are knit, and returning the loops from the points to the needles during a narrowing cycle.

3. The method of knitting a complete hose fabric upon a flat full fashioned machine by holding the instep loops off the needles while the heel tabs are knit, which comprises receiving upon points during a knitting cycle the instep loops and also loops beyond the ends thereof from which portions at the inner edge of the heel tabs will be knit, retaining the loops so received while the heel tabs are knit, and returning the loops from the points to the needles during a narrowing cycle.

4. The method of knitting a complete hose fabric upon a flat full fashioned machine which comprises placing a plurality of loop receiving points on the beardless sides of a series of needles at the central portion of the fabric, moving the points and the needles through a regular knitting motion to cast the loops off the needles

and cause them to be received upon the points, and continuing knitting from the loops at the sides of the fabric including at least one of the loops received upon the end points.

5. The method of knitting a complete hose fabric upon a flat full fashioned machine which comprises placing a plurality of loop receiving points on the beardless sides of a series of needles at the central portion of the fabric, supplying yarn to at least the end needles against which the points are positioned and also to the needles outwardly therefrom, and moving the needles through a knitting cycle to cast off all the loops from the needles and knit the new yarns, the points being moved with the needles during the casting off portion of their motion to cause the loops to be received upon the points.

6. A full fashioned leg and foot hosiery knitting machine comprising a needle bar having a plurality of spring beard needles, a plurality of loop receiving points, means for supporting said points, means for giving the needles their knitting movement, and means for operating the points to position them against the beardless or back side of the needles and causing them to move with the needles through at least that part of the knitting motion which serves to cast off loops in the usual manner from the needles, whereby the loops will be left on the points.

7. A full fashioned leg and foot hosiery knitting machine comprising a needle bar having a plurality of spring beard needles, a plurality of loop receiving points, means for supporting said points, means for giving the needles their knitting movement, and means for operating the points to position them against the beardless or back side of the needles and causing them to move with the needles through at least that part of the knitting motion which serves to cast off loops in the usual manner from the needles, whereby the loops will be left on the points, and means for returning the loops on the points to the needles during a narrowing motion.

8. A full fashioned leg and foot hosiery knitting machine comprising a needle bar having a plurality of spring beard needles, means for moving the bar through its knitting motions, a plurality of points for holding some of the fabric loops while knitting progresses from the other fabric loops, a hanging frame carrying said points, a pivotal support for said frame, and means for moving the points back and forth with the needles during knitting including a lever pivotally connected at a point between its ends to the hanging frame and connected at its lower end to the needle bar, and means forming a pivot for the upper end of said lever.

9. Apparatus according to claim 8 in which the pivot for the upper end of said lever is adjacent to the pivotal support for the hanging frame.

10. Apparatus according to claim 8 in which the connection between the lower end of the lever and the needle bar includes a cam whereby vertical movements of the needle bar will cause a relative movement along the cam and maintain the horizontal spacing between the points and needles.

11. Apparatus according to claim 8 in which the connection between the lower end of the lever and the needle bar is disconnectable, and said pivotal connection between the lever and the hanging frame includes another pivot which permits movement of the lever to disengage said disconnectable connection.

12. Apparatus according to claim 8 including means for holding the pivot at the upper end of said lever in fixed position during the engagement of said disconnectable connection to cause their engagement as the hanging frame moves into operative position.

13. Apparatus according to claim 8 including a cam acting upon the upper end of the lever to move it and thereby the points progressively away from the needles as knitting proceeds.

14. A full fashioned leg and foot hosiery knitting machine comprising a needle bar having a plurality of spring beard needles, means for moving the bar through its knitting motions, a plurality of points for holding some of the fabric loops while knitting progresses from the other fabric loops, a hanging frame carrying said points, a pivotal support for said frame, a lever pivotally connected to the hanging frame, means at the lower end of the lever for establishing a connection with the needle bar to move the frame and cause motion of the points with the needles, and means acting upon the lever to retain the lever relative to the frame as the lower end of the lever moves toward the needle bar to cause engagement of the connection between the needle bar and the lever.

15. Apparatus according to claim 14 including cam means acting upon the lever for causing its disengagement from the needle bar.

16. A full fashioned leg and foot hosiery knitting machine comprising a needle bar having a plurality of spring beard needles, means for moving the bar through its knitting motions, a plurality of points for holding some of the fabric loops while knitting progresses from the other fabric loops, a hanging frame carrying said points, a pivotal support for said frame, and means for moving the points back and forth with the needles during knitting including a lever pivotally connected to the hanging frame, means connecting the lever to the needle bar to move the points back and forth with the needles, and cam means acting upon the lever to move the points progressively away from the needles as knitting proceeds.

17. Apparatus according to claim 16 in which said cam means includes a cam portion for moving the lever to disengage the connection between the lever and the needle bar.

18. A full fashioned leg and foot hosiery knitting machine comprising a needle bar having a plurality of spring beard needles and main cam shaft, means for moving the bar through its knitting motions, a plurality of points for holding some of the fabric loops while knitting progresses from the other fabric loops, a hanging frame carrying said points, a pivotal support for said frame, means for actuating said frame including an auxiliary cam shaft and cams thereon having connections to the frame, means for rotating the cam shaft including a cam upon the main cam shaft and a cam follower continuously operated thereby, driving connections leading from the cam follower to the auxiliary cam shaft to drive the latter, said driving connections including members disengageable from each other, and pattern means for establishing engagement or disengagement between said disengageable members of said driving connections to cause rotation of the auxiliary cam shaft only at predetermined times.

19. A full fashioned leg and foot hosiery knitting machine comprising a needle bar having a plurality of spring beard needles, means for mov-

ing the bar through its knitting motions, a plurality of points for holding some of the fabric loops while knitting progresses from the other fabric loops, a hanging frame carrying said points, means for operating the frame, a pivotal support for said frame, cam means having a connection to the frame to force the points progressively away from the needles as knitting proceeds, and a pawl and ratchet mechanism for rotating the cam, said ratchet having a cut away portion in which the pawl will have idle movement to cause the cam to come to rest after one turn.

20. Apparatus according to claim 19 in which the pawl is supported by a fixed part of the machine and the cam is associated with the hanging frame, whereby the relative movement of the hanging frame to place it into operative position will remove the pawl from said cut away portion and bring the pawl into operative relation with respect to the ratchet.

21. A full fashioned leg and foot hosiery knitting machine comprising a needle bar having a plurality of spring beard needles, means for moving the bar through its knitting motions, a plurality of points for holding some of the fabric loops while knitting progresses from the other fabric loops, a hanging frame carrying said points, means for operating the frame, a pivotal support for said frame about which the frame may be turned up to an inoperative position or lowered by gravity to an operative position, and means for initiating movement of the frame at a predetermined time from its operative to its inoperative position, including a pattern controlled cam and connections therefrom to the frame for giving it an initial movement to a position from which it will fall by its own weight to its lowered operative position.

22. A full fashioned leg and foot hosiery knitting machine comprising a needle bar having a plurality of spring beard needles, means for moving the bar through its knitting motions, a plurality of points for holding some of the fabric loops while knitting progresses from the other fabric loops, a hanging frame carrying said points, means for operating the frame, a pivotal support for the frame about which it may be turned up to an inoperative position or lowered to an operative position, means for automatically urging the frame from its inoperative to its operative position at a predetermined time, cam means having a connection to the frame to force the points progressively away from the needles, and another cam rotatable with said cam means and operatively associated with the hanging frame to prevent its fall if the cam means is in an incorrect initial position.

23. A full fashioned leg and foot hosiery knitting machine comprising a needle bar having a plurality of spring beard needles and a narrowing frame, means for moving the bar through its knitting motions, a plurality of points for holding some of the fabric loops while knitting progresses from the other fabric loops, a hanging frame carrying said points, arms providing a pivotal support for the upper end of the hanging frame, said arms being secured to a shaft which is pivotally mounted in the narrowing frame, and means acting upon the shaft when the machine passes through its narrowing motion to cause rotation of the shaft to thereby lift the hanging frame and maintain its vertical position relative to the machine as the narrowing frame descends.

24. Apparatus according to claim 23 in which

said means acting upon the shaft includes an arm pivoted upon the shaft and having a cam face, and a disengageable connection between the arm and the shaft.

25. A full fashioned leg and foot hosiery knitting machine comprising a needle bar having a plurality of spring beard needles, means for moving the bar through its knitting motions, a plurality of points for holding some of the fabric loops while knitting progresses from the other fabric loops, a hanging frame carrying said points, loop enlarging means for association with certain of the needles when the points are in operation, a pivotal support for said loop enlarging means whereby they may be placed into operative or inoperative position, and means for automatically placing them in operative position including a trip associated with the pivotal support and a pattern controlled member brought into relation to be engaged by said trip as the needle bar passes through its knitting motion.

26. Apparatus according to claim 25 including means for automatically restoring the loop enlarging points to inoperative position, said restoring means comprising a lug associated with the pivotal support and a pattern controlled member brought into relation to be engaged by said lug and exert a turning motion on the pivotal support for the loop enlarging means.

27. The method of knitting a complete hose fabric upon a flat full fashioned machine which comprises locating loop receiving points on the beardless sides of the needles from which loops are to be received, and operating the needles through a knitting cycle so that the loops will be cast off the needles and be received by the points, said points receiving the instep loops and also at least one loop beyond both ends of the instep row.

28. A full fashioned leg and foot hosiery knitting machine comprising a needle bar having a plurality of spring beard needles, a plurality of loop receiving points, means for supporting said points, means for giving the needles their knitting movement, and means for operating the points to position them against the beardless or back side of the needles and causing them to move with the needles through a part of the knitting motion to cause the points to receive the cast off loops, and means for returning the loops on the points to the needles during a narrowing motion, said points being sufficient in number to receive the instep loops and at least one loop beyond each end of the instep row from which the inner selvage of the heel tabs will be knit.

29. A full fashioned leg and foot hosiery knitting machine comprising a needle bar having a plurality of spring beard needles, a plurality of loop receiving points, means for supporting said points, means for giving the needles their knitting movement, and means for operating the points to position them against the beardless or back side of the needles and causing them to move with the needles through a part of the knitting motion to cause the points to receive the cast off loops, and means for returning the loops on the points to the needles during a narrowing motion, said needles having eyes in their beardless sides to receive the tips of the points.

30. A full fashioned leg and foot hosiery knitting machine comprising a needle bar having a plurality of spring beard needles and a main cam shaft, means for moving the bar through its knitting motions, a plurality of points for holding some of the fabric loops while knitting progresses

from the other fabric loops, a hanging frame carrying said points, a pivotal support for said frame, means for actuating said frame including an auxiliary cam shaft and cams thereon having connections to the frame, means for rotating the cam shaft including a cam upon the main cam shaft and a cam follower, driving connections leading from the cam follower to the auxiliary cam shaft to drive the latter, and pattern means for establishing engagement or disengagement between said cam follower and said driving connections to cause rotation of the auxiliary cam shaft only at predetermined times, said driving connections including a detent engaging with said pattern means after a single motion of the auxiliary cam shaft to prevent its repeated motion.

31. A full fashioned leg and foot hosiery knitting machine comprising a needle bar having a plurality of spring beard needles, means for moving the bar through its knitting motions, a plurality of points for holding some of the fabric loops while knitting progresses from the other fabric loops, a hanging frame carrying said points, means for operating the frame, a pivotal support for said frame about which the frame may be turned up to an inoperative position or lowered to an operative position, and means for urging the frame at a predetermined time from its operative to its inoperative position, including

it, operative to its operative position, including a pattern controlled cam and connections therefrom to the frame for giving it an initial movement to its lowered operative position, and a suction piston and cylinder operatively connected to the frame and to the machine to retard the falling movement of the frame.

32. A full fashioned leg and foot hosiery knitting machine comprising a needle bar having a plurality of sprung board needles, means for moving

plurality of spring beard needles, means for moving the bar through its knitting motions, a plurality of points for holding some of the fabric loops while knitting progresses from the other fabric loops, a hanging frame carrying said points, means for operating the frame, a pivotal support for said frame about which the frame

support for said frame about which the frame 5 may be turned up to an inoperative position or lowered to an operative position, and means for urging the frame at a predetermined time from its operative to its inoperative position, including a pattern controlled cam and connections there- 0 from to the frame for giving it an initial movement to its lowered operative position, and a suction piston and cylinder operatively connected to the frame and to the machine to retard the

5 falling movement of the frame, said cylinder having a port opening therethrough to release the suction therein and cause a final rapid falling motion of the frame to cause engagement between the frame and its operating means.

33. A full fashioned leg and foot hosiery knitting machine comprising a needle bar having a plurality of spring beard needles, means for moving the bar through its knitting motions, a plurality of points for holding some of the fabric loops while knitting progresses from the other fabric loops, a hanging frame carrying said points, means for operating the frame, a pivotal support for said frame about which the frame may be turned up to an inoperative position or lowered to an operative position, and means for urging the frame at a predetermined time from its operative to its inoperative position, including a pattern controlled cam and connections therefrom to the frame for giving it an initial movement to its lowered operative position, and a suction piston and cylinder operatively connected

to the frame and to the machine to retard the falling movement of the frame, said cylinder having a port opening therethrough to release the suction therein and cause a final rapid falling motion of the frame to cause engagement between the frame and its operating means, the engagement between the frame and its operating means including a spring pressed pin on the one and a member on the other having a recess therein to receive the pin and an incline to depress the pin and allow it to enter the recess during said final rapid movement of the frame.

34. Steps in a method of knitting full fashioned hosiery consisting in locating a loop receiving point on the beardless side of at least one needle immediately beyond each end of and in line with the row of instep loops, which points will receive the loops from said needles when cast off during a knitting cycle, said loops remaining on said points during the knitting of the heel tabs, thereafter causing said points to restore said loops to

5 the needles from which they were cast off, then turning the heel tabs outwardly and impaling the loops of a wale of each tab onto the needles and continuing the knitting to form the foot, substantially as described.

10 35. A full fashioned leg and foot hosiery knitting machine comprising a row of needles for knitting instep fabric and other needles beyond each end of said row for knitting heel tabs and other portions of the fabric, a loop receiving point for at least one of said other needles beyond each end of the said instep row, means for operating the needles through a knitting cycle to cast off their loops whereby said points will receive loops, means for operating the machine for knitting the heel tabs while said cast off loops remain on the said points and for thereafter causing said points to restore said loops to the needles from which they were cast off, for participating in further knitting to form the foot fabric.

20 KENNETH HOWIE.
